UNITED STATES PATENT OFFICE.

WILLIAM T. BRADSHAW AND ARTHUR J. BOND, OF OAKLAND, CALIFORNIA.

DESIGN FOR A BOTTLE-HOLDER.

58,014.

Specification for Design.

Patented May 31, 1921.

Application filed October 25, 1920. Serial No. 419,229. Term of patent 14 years.

To all whom it may concern:

Be it known that we, WILLIAM T. BRADSHAW and ARTHUR J. BOND, citizens of the United States, residing at Oakland, in the county of Alameda and State of California, have invented a new, original, and ornamental Design for Bottle-Holders, of which the following is a specification, reference being had to the accompanying drawing, forming a part thereof.

Fig. 2 is a view in plan of the same.
Fig. 3 is a view in front elevation of the same.

We claim:
The ornamental design for a bottle holder as shown.

In testimony whereof we affix our signatures.

WILLIAM T. BRADSHAW.
ARTHUR J. BOND.
